ATTORNEY'S

UNITED STATES PATENT OFFICE

SAMUEL SHAFER, JR., OF MILWAUKEE, WISCONSIN, ASSIGNOR TO CHAIN BELT COMPANY, OF MILWAUKEE, WISCONSIN, A CORPORATION OF WISCONSIN

AGITATING ATTACHMENT FOR VEHICLE BODIES

Application filed April 20, 1929. Serial No. 356,765.

This invention relates to agitating attachments for vehicle bodies and has for one of its objects to provide a device of this character which will be simple in construction, comparatively inexpensive to manufacture, and more efficient in use than those which have been heretofore proposed.

A further object of the invention is to provide a simple and effective means which may be readily attached to and detached from the body of a standard motor truck or other similar vehicle, and which may be employed for the agitation of premixed concrete or other similar materials.

With the above and other objects in view, which will appear as this description proceeds, the invention consists in the novel details of construction and combinations of parts more fully hereinafter described and particularly pointed out in the appended claims.

Referring to the accompanying drawings forming a part of this specification in which like reference characters designate like parts in all of the views:—

Figure 1 is a side elevational view, partly broken away, of a motor vehicle with an agitating attachment constructed in accordance with the present invention in place thereon;

Figure 2 is a top plan view of the truck body and agitating attachment shown in Fig. 1;

Figure 3 is a transverse sectional view taken approximately on the plane indicated by the line 3—3 of Fig. 1 looking in the direction of the arrows;

Figure 4 is a view similar to Fig. 3 and taken on substantially the same plane but looking in the opposite direction; and

Figure 5 is a detail side elevational view of the agitator detached from the body.

Referring more particularly to said drawings, numeral 10 indicates generally a motor vehicle such as a motor truck having a chassis 11 upon which is mounted the load-receiving

body 12 which may be of metal or other suitable construction. The said body may be of the well known dumping type provided with a pivotal tail gate 13 adapted to be elevated for dumping by means of a suitable power or hand driven hoist 14.

In present day concrete practice it has become quite common to mix the concrete at a central plant, which is conveniently located as to transportation facilities for the raw materials, and to then transport the mixed concrete to the point of use in motor trucks or other similar vehicles. It has been found, however, that during such transportation the concrete materials have a tendency to separate, with the heavier aggregates settling to the bottom and the water and cement floating above them.

To overcome this objection numerous means have been proposed for continuously agitating the mixed concrete during transit whereby the separation of the materials is prevented.

Most of the apparatus heretofore proposed has contemplated the provision of special bodies or vehicles for the transportation, which special means are a considerable expense to the contractor who as a rule already owns one or more motor trucks. The present invention provides an attachment for the standard motor trucks which may be readily attached to such trucks as the contractor may already own and which may be readily transferred from one truck to another in the event of a breakdown or the discharging of a particular truck.

As will be clear from the drawings, the present invention comprises transverse supporting members 15 which are adjustable as at 16 to accommodate them to truck bodies of different widths and which are adapted to be detachably secured to the sides of the truck body 12 at 17. Upon these said supporting members 15 there is mounted a prime mover, such for example, as a gasoline engine 18.

Additional transverse supporting members 20, which are adjustable as at 21, are provided at the front and rear ends of the body 12 which likewise are detachably secured to the sides of the said body as at 22, and the said members are provided with bearings 23 in which are journalled the longitudinally extending shafts 24. The said shafts are provided with a plurality of agitating paddles 25, the paddles of each shaft being preferably arranged in two series which are oppositely inclined, whereby the front series will tend to move the concrete rearwardly while the rear series would tend to move the concrete forwardly.

The shafts 24 adjacent their forward ends pass through a division plate 26 which extends transversely of the vehicle body to form a forward compartment 27 from which concrete material is excluded and in which is mounted the driving means for said shafts. These driving means as here shown comprise sprocket wheels 28 carried by the shafts and a sprocket chain 29 engaging therewith, which chain also engages with a sprocket wheel 30 carried by the power shaft of the motor 18. A suitable clutch controlled by a clutch lever 31 may be interposed in the power line whereby the apparatus may be stopped and started at will.

Substantially midway between the ends of the body there is provided another pair of transversely extending adjustable supporting members 35 upon which is mounted a sprocket wheel 36. A sprocket chain 37 is trained about the said wheel and also about similar sprocket wheels 38 carried by the agitating shafts 24. The chain 37 is provided with a plurality of agitating flights 39 which further serve to agitate the concrete as it is moved toward the center of the body by the paddles 25 as above described.

The manner of employing the invention will be clear from the foregoing, it being understood that after the device has been attached to the body of the motor truck, the said body is loaded with premixed concrete for transportation from the central plant to the point of use. During transit the motor 18 is operated to drive the shafts 24 which through their agitating paddles 25 and the transverse agitator 39 will maintain the concrete in mixed condition and prevent the separation of the materials. The agitator being a complete unit in itself may be readily detached from a truck which becomes disabled and transferred to another truck; and it may be readily applied to trucks having bodies of different dimensions. The agitators may obviously be bought separately and applied to trucks which are already in use.

If desired the transverse agitator 39 may be omitted as it is not absolutely essential to the operation of the device.

While one form of the invention has been

illustrated and described it is obvious that those skilled in the art may vary the details of construction as well as the precise arrangement of parts without departing from the spirit of the invention and therefore, it is not wished to be limited to the above disclosure except as may be required by the claims.

What is claimed is:

1. An agitating attachment for vehicle bodies, comprising a plurality of adjustable frame members adapted to be readily attached to and detached from the body; shafts having agitating paddles journaled in said members; a motor also carried by said members; and driving connections between said motor and shafts.

2. An agitating attachment for vehicle bodies, comprising a plurality of adjustable frame members adapted to be readily attached to and detached from the body; shafts provided with agitating paddles journaled in said members; a motor also carried by said members; driving connections between said motor and shafts; and a partition plate between said connections and paddles.

3. An agitating attachment for vehicle bodies, comprising a plurality of frame members adapted to be readily attached to and detached from the body; a longitudinally operating agitator carried by said members; a transversely operating agitator also carried by said members; and a motor mounted on said members for driving both of said agitators.

In testimony whereof I affix my signature.
